UNITED STATES PATENT OFFICE.

ARCALOUS WYCKOFF AND ERNEST L. WYCKOFF, OF ELMIRA, NEW YORK.

WOOD-DRYING KILN.

SPECIFICATION forming part of Letters Patent No. 388,102, dated August 21, 1883.

Application filed September 9, 1886. Serial No. 213,136. (No model.)

To all whom it may concern:

Be it known that we, ARCALOUS WYCKOFF and ERNEST L. WYCKOFF, of Elmira, in the county of Chemung and State of New York, 5 have made certain new and useful Improvements in Wood-Drying Kilns, of which we declare the following to be a full, clear, and concise specification.

Our invention relates to improvements in 10 wood-drying kilns; and the novelty consists in a kiln of the class named, having an enclosed chamber to receive the material to be dried, a series of inclined deflectors or tables by which said material is more fully exposed 15 to the action of heat within said chamber, a series of circulating-pipes adapted to be heated by steam, and means to cause currents of heated air to pass to and through the inclined deflectors and the material thereon, all substantially as hereinafter set forth, and illustrated in the accompanying drawings, wherein similar figures of reference denote similar parts.

In said drawings, Figure 1 is a side elevation of a kiln constructed in accordance with 25 our invention. Fig. 2 is a central longitudinal section therethrough. Fig. 3 is a transverse section through said kiln, and Fig. 4 is a plan view thereof.

In the present embodiment of our invention 30 we provide a chamber, 1, which is formed within a shell or casing, 2, constructed of any desired suitable material—as stone, brick, slate, iron, &c.—with two main or principal deflecting-tables, 3, which are formed of a series of 35 slats, 4, that extend from longitudinally-extending rails 5, secured to opposite sides of the chamber 1, at or near the bottom thereof, upward and inward to a rail, 6, at or near the middle of the chamber 1.

Immediately above the deflectors 3, and below the middle of the opening 7, through which the kiln is charged, we arrange a second pair 40 of deflectors, 8, which are smaller than and have a similar construction to the tables 3, and are supported upon rails 9 and 10, which extend from end to end of the chamber, and struts or braces 11, which abut upon the ridge or apex of the tables 3 and extend thence to the rails 9 and 10, respectively.

50 We provide the opposite surfaces of the

chamber 1 in the plane of the tables 8 and the middle of the tables 3 with outwardly-inclined tables 12 and 13, which are formed in manner similar to the tables 3 and 8, and are supported by rails 14 and 15 and struts 16 and 17. We 55 arrange a series of deflectors, 18 and 19, at points intermediate of the deflecting-tables hereinbefore described, each of which deflectors consist of oppositely-inclined tables 20 and 21, supported upon rails 22 and struts 23. 60

By reference to Fig. 2 it will be observed that the tables 20 would, if extended, join the tables 8 and 12 at or near the middle of the latter, while said latter tables would, if extended, join the tables 21 immediately below 65 the junction of said table, while the latter are arranged, as regards the tables 13 and 3, in manner similar to their fellows, as above described.

By the described construction or arrangement of the several deflecting-tables, material, and particularly kindling-wood, which the chamber 1 is designed and adapted to receive, would, if thrown upon the upper deflectors, pass downward from table to table until it 70 reached apertures 24, formed through the opposite sides of the casing 2, immediately above the junction of the tables 3 therewith, for the purpose of removing the material from the kiln. 75

It will also be apparent that the kindling-wood will, in its passage from top to bottom of the chamber 1, be thrown about, and so be fully exposed to the action of heat generated within said chamber by a series of steam-receiving 80 coils or pipes, 25 and 26, which are located beneath the tables 3 and 13, respectively.

A constant circulation of air is maintained within the chamber 1 by either a blast-fan or blower, 27, connected with the bottom of the 85 chamber 1, or an exhaust-fan, 28, connected with the upper portion of said chamber.

It will be understood that moist vapors from the wood will pass to and escape through a flue, 29, with which the kiln is provided.

If desired, the openings 24 may extend from 90 end to end of the chamber 1, as shown by full lines in Fig. 1, or a series of smaller openings may be formed; also, said openings may be provided with flaps or doors 30, as shown in Fig. 95 100

3. When the openings 24 are small, as shown by the dotted lines in said Fig. 1, a series of inclined tables, 31, which are arranged perpendicularly to the tables 3, may be employed 5 to deflect the wood to such openings.

In practice steam is admitted to the coils 25 and 26, to heat the interior of the kiln, after which kindling wood, which consists, as is well known, in small pieces of wood, is admitted 10 to the chamber 1 through the opening 7, and, falling to the deflectors or inclined tables, is diverted from a direct downward course and passed back and forth from table to table until it reaches the discharge openings 24.

It will be understood that the position of the wood while passing down the inclined tables will be changed—that is to say, that portion of the wood which was underneath upon the 20 one table will be upon the top upon the next lower table; also that such change of position of the wood will continue until the lowest limit of movement is reached thereby.

We have herein described and prefer to heat 25 the chamber 1 by steam, which is admitted to the pipes or coils 25 and 26, as we have found such method to be the best in practice. If desired, however, heated air may be used in said pipes in lieu of steam.

30 If desired, a damper may be arranged within the flue 29, as indicated at 32.

If desired, the chamber 1 may be charged through the flue 29.

It will be seen that the two main deflecting 35 tables extend high up into the chamber, the heating-coils being arranged nearly or quite to the upper portion thereof, and that the inclined tables 13 (beneath which are steam-coils) are opposite the main tables 3, while 40 between these tables, beneath which are placed the heating-coils, are arranged the deflectors 19 and 21, which insure that the wood shall be caused to travel over practically the whole surface of these tables, in close proximity to 45 which are the heating-coils. By this arrangement we have found that a most thorough exposure of the wood to the drying heat is obtained in a device wherein the material passes automatically through the drier.

50 The tables 13 eventually deliver the mate-

rial which has been exposed thereon to the main tables 3, which terminate opposite the delivery-openings 24.

Various modifications in detail of construction may be made in the within-described invention without departing from the spirit thereof, which contemplates a drying-chamber heated by a series of steam-receiving coils or pipes and provided with inclined deflectors, which are arranged to permit the passage of 60 heated air therethrough to and about the material thereon.

We claim—

1. In a kiln for drying kindling-wood, a casing having an inclosed chamber and an exhaust 65 apparatus for taking away air and vapor from the top thereof, in combination with main deflecting slatted tables 3, situated in the lower part of the chamber, heating-coils arranged beneath the tables, inclined slatted tables 13, 70 situated at the sides of the chamber opposite tables 3, other heating-coils arranged beneath tables 13, and inclined deflectors of inverted-V shape, also of slats, and arranged to direct the material to the said tables and to form 75 open spaces throughout the mass of wood being dried, and means for furnishing air to the heaters, whereby it is first heated and then passed through the entire mass of wood, the slatted tables and deflectors facilitating such 80 passage, substantially as set forth.

2. A casing inclosing a chamber, 1, having openings 24 formed at its opposite sides, and oppositely-inclined tables 3, formed of slats 4, terminating opposite said openings, in combination with a series of smaller grated inclined deflectors arranged above and at the sides of said tables 3 and delivering thereon, and a series of steam-receiving pipes or coils below each of said tables, and an exhaust fan or 90 blower, substantially as described.

In testimony whereof we have signed our names to this specification in the presence of two subscribing witnesses.

ARCALOUS WYCKOFF.
ERNEST L. WYCKOFF.
